TOY

George H. Driscoll, Louisville, Ky., assignor of
one-half to Leo S. Baron, Louisville, Ky.

Application July 8, 1937, Serial No. 152,607

2 Claims. (Cl. 273—95)

This invention relates, as indicated, to a toy, but has reference more particularly to a toy of the class wherein a ball is struck by means of devices held and manipulated by the hands of the user or player.

5 A primary object of the invention is to provide a toy of the character described which is designed to afford exercise as well as amusement or recreation.

10 Another object of the invention is to provide a toy of the character described which can be easily manufactured in commercial quantities at relatively low cost.

15 A further object of the invention is to provide a toy of the character described, the use of which requires or involves movements which simulate the exercise of punching a bag.

20 Other objects and advantages of the invention will be apparent during the course of the following description.

In the accompanying drawing, forming a part of this specification, and in which like numerals are employed to designate like parts throughout the same,

25 Fig. 1 is a perspective view of a toy embodying the principal features of the invention;

Fig. 2 is a plan view of one of the punching devices or hand paddles, and

30 Fig. 3 is a transverse cross-sectional view through the punching device, taken on the line 3—3 of Fig. 2.

35 In the drawing, wherein for the purposes of illustration, there is shown a preferred embodiment of my invention, the toy is seen to comprise a pair of handles or hand paddles generally designated by the reference numeral 1, extensible elastic or rubber bands 2 secured at one end to said hand paddles and a ball 3 of rubber or the like, to diametrically opposite points of which the other ends of the bands 2 are secured. The ball, 40 in other words, is tethered to each of the hand paddles.

45 Each of the handles or hand paddles comprises a plate 4, a hand grip 5 and end struts 6 which interconnect the plate and hand grip, these parts being secured together in any suitable or desired manner, as, for example, by nailing. The plate 4, in practice, is from three to four inches wide and from four to five inches long, and is 50 preferably rounded at the corners, as shown.

55 The hand grip 5 is about one inch wide and from four to five inches long. The end struts 6 are tapered from top to bottom, as shown. The plates 4, hand grips 5 and end struts 6 are preferably made from plywood or laminated wood, about one-fourth of an inch thick, such material

being preferred due to its lightness, freedom from warpage, and the ease with which it may be cut or sawed or finished.

The ball 3 is preferably a hollow rubber ball, from about one and one-half to about two and one-half inches in diameter, although it is to be understood that a solid rubber ball may be employed or a ball of any other resilient material.

The bands 2 are of substantial thickness and are secured to the centers of the plates 4 and to 10 diametrically opposite points of the ball in any desired manner. For best results, the bands, in unstretched condition, should be approximately five or six inches long. If desired, a single rubber band may be employed instead of two rubber 15 bands, in which event, the band will extend entirely through the ball.

In using the toy, the player or user will grip the hand grip of one of the hand paddles with the right hand and the hand grip of the other hand paddle with the left hand, permitting the ball to dangle. He will then punch the ball in the same manner that a punching bag is punched, punching the ball alternately with each of the plates 4. By repeated practice, skill and proficiency in punching the ball are soon acquired, and a considerable amount of pleasure and exercise derived therefrom.

It is to be understood that the form of the invention herewith shown and described, is to 30 be taken as a preferred example of same, and that various changes in the shape, size and arrangement of parts may be resorted to, without departing from the spirit of the invention or the scope of the subjoined claims.

35 Having thus described my invention, I claim:

1. A toy of the character described adapted for use in exercising in a manner simulating the punching of a punching bag with both fists, said toy comprising a ball, a plurality of ball punching devices, each of said devices comprising a substantially flat portion one face of which is adapted to strike the ball and a rigid handle rigidly secured to the opposite face of said flat portion and adapted to be gripped by a user of 40 the toy, and extensible members interconnecting said ball and said devices, each of said members being secured at one end of said ball and at the other end to one of said devices at substantially the central point of the ball striking face of the 45 latter.

2. A toy, as in claim 1, in which the extensible members are connected to said ball at substantially diametrically opposite points of the latter.

GEORGE H. DRISCOLL. 55
